CONTINUOUS CHILLING PROCESS FOR DEWAXING

Filed March 18, 1938

UNITED STATES PATENT OFFICE

2,202,542

CONTINUOUS CHILLING PROCESS FOR
DEWAXING

Vanderveer Voorhees, Hammond, Ind., assignor
to Standard Oil Company, Chicago, Ill., a cor-
poration of Indiana

Application March 18, 1938, Serial No. 196,608

10 Claims. (CL 196—18)

This invention relates to a continuous chilling process and it pertains more particularly to a process of dewaxing mineral oils diluted with a normally gaseous hydrocarbon such as propane.

It is extremely important in dewaxing processes that the wax be crystallized from the oil in readily separable form so that when the chilled wax slurry is filtered, settled or centrifuged a substantially oil-free wax and a large yield of dewaxed (low pour point) oil will be obtained. It has been found that propane is an excellent diluent for accomplishing these results, but in all propane dewaxing plants that have been constructed, it has been necessary to employ batch chilling in order to prevent the flashing of propane at a point of pressure release with consequent shock chilling. An object of my invention is to provide a continuous method of chilling a wax mixture which will avoid shock chilling and which will produce readily separable wax crystals and thereby lead to the production of large oil yields and oil-free waxes.

A further object of the invention is to provide a simple and efficient dewaxing system which will involve lower capital expenditures and lower operating costs than dewaxing systems heretofore known. A further object is to increase the uniformity of operation of a dewaxing system and the uniformity of products produced by said system.

A further object is to provide means for accurately controlling the temperature gradient in a continuous chilling tower. A further object is to utilize effectively the refrigeration value of the cold filtrate in a dewaxing process. A further object is to reduce compressor costs in a dewaxing process by carrying out the entire process under relatively high pressures. Other objects will be apparent as the detailed description of my invention proceeds.

The present invention is an improvement and continuation-in-part of my prior application Serial No. 733,271, filed June 30, 1934, and issued as Patent No. 2,127,708 on August 23, 1938, in which I describe the vaporization of propane from an oil-propane solution at substantially constant pressure, the vaporization being effected by the circulation of a current of inert gas. I have found that carbon dioxide is an excellent inert gas for use in this system, and that the carbon dioxide may be liquefied and then vaporized in the chilling tower to increase the efficiency and effectiveness of the chilling operation. An important feature of my invention is the accurate control of the temperature gradient

throughout the chilling tower by the introduction of liquid carbon dioxide in regulated amounts at a plurality of spaced points along the length of the tower, the carbon dioxide being introduced out of contact with the liquid oil-wax mixture. 5 The carbon dioxide which is thus introduced not only effects chilling by its own vaporization, but it brings about further vaporization of the propane from the diluted oil-wax mixture at the point of introduction. The carbon dioxide and 10 propane vapors leave the top of the tower at about 150 to 200 pounds pressure so that with slight additional compression a substantial part of the propane may be liquefied with ordinary condenser water and the carbon dioxide may be 15 liquefied by contact with the cold filtrate. The liquefied carbon dioxide may then be reintroduced at the spaced points along the chilling tower.

The invention will be more clearly understood from the accompanying drawing which forms a 20 part of this specification and which diagrammatically illustrates my improved chilling and dewaxing system.

The invention will be described in connection with the dewaxing of a deasphalted Mid-Continent residual lubricating oil stock, but it should be understood that the invention is equally applicable to distillate stocks and to crudes from any and all sources. In my preferred embodiment I use propane as a diluent, but it should be understood that other normally gaseous hydrocarbons, such as ethane, iso-butane, normal butane, ethylene, propylene, the butylenes and mixtures of any two or more of these hydrocarbons with each other or with other diluents. The invention 30 is also applicable to the use of non-hydrocarbon diluents, particularly wax anti-solvents such as dimethyl ether, sulfur dioxide, etc. Certain aspects of the invention may be employed with less volatile diluents such as naphthas, acetone, 35 methyl ethyl ketone, benzol acetone mixtures, methyl ethyl ketone benzol mixtures and other known dewaxing diluents.

The deasphalted residual lubricating oil stock is charged to the system through line 10 and 45 mixed with about 2 to 4 volumes of propane withdrawn from storage tank 11 through line 12. Suitable pumps in lines 10 and 12 proportion the mixture of oil and propane and effect the introduction of this mixture through line 13 into 50 cooling tower 14 which is maintained at a pressure of about 150 to 200 pounds per square inch. It should be understood, however, that the pressure in this tower will vary with different diluents and different chilling temperatures and may 55

range from about 50 to 250 pounds per square inch. With the above-described propane mixture introduced at a temperature of about 100° F. and withdrawn from the base of the tower at a 5 temperature of about -40° F., I prefer to operate the tower at a pressure of about 150 pounds per square inch. It should be understood that the oil-propane mixture may be heated to temperatures of 140° to 190° F. and subsequently cooled 10 to about 80° to 100° F. in cooling water exchangers before being introduced into the top of the chilling tower.

Chilling tower 14 is preferably provided with a series of alternating baffle plates 15, which are 15 so arranged that the liquids will cascade from plate to plate in the course of their flow from the top to the bottom of the tower. Along the length of the tower I provide a carbon dioxide header 16 and from this header a plurality of valved carbon 20 dioxide injectors 17 lead to spaced points in the tower underneath said spaced baffle plates 15. The liquefied gas is introduced out of direct contact with liquids in the tower, so that shock chilling is avoided.

25 As the propane-oil solution enters the tower through line 13 there will be no appreciable flashing of propane because of the high pressure which is maintained within the tower. Propane will evaporate, however, from this mixture into 30 the upwardly-flowing stream of carbon dioxide, and this gradual and uniform vaporization of propane will effect the desired continuous refrigeration. To assure the uniformity of cooling throughout the length of the tower I introduce 35 the carbon dioxide in regulated amounts at spaced points along the entire length of the tower. The carbon dioxide thus introduced through injectors 17 effects a certain amount of cooling due to the absorbed heat of vaporization 40 when the liquid carbon dioxide is vaporized. Furthermore, at each point of introduction there will be provided a carbon dioxide atmosphere into which propane may vaporize, so that the vaporization of propane is augmented by its partial 45 pressure. The amount of cooling at any particular portion of the tower can be determined by the amount of liquid carbon dioxide which is introduced at that point, and by proper regulation of valves in injectors 17, for instance 50 by thermostatic controls 17a, a uniform temperature gradient can be maintained throughout the length of the tower. The valves in injectors 17 are preferably thermostatically controlled in accordance with tower temperature so that regulation 55 is continuous and automatic.

For a tower pressure of about 150 pounds the slurry withdrawn from the base of the tower will be at a temperature of about -40° F., and it may be introduced directly through line 18 to 60 the bowl of continuous filter 19, although any conventional separating means may be used. The filter is preferably of the type described in U. S. Patent 2,050,007. A feature of my invention is the use of the tower pressure for operating the filter so that no mechanical pumps of any kind are required. This is important because mechanical pumps tend to macerate and destroy the wax crystals, and to make filtration more difficult.

70 Filtrate is withdrawn through line 20, heat exchanger 21 and line 22 to high pressure oil still 23 which may be operated at a pressure of about 200 pounds per square inch, and which is provided with a suitable heater such as steam coil 24. Most of the propane and dissolved car-

bon dioxide is withdrawn through line 25, cooled by condenser water in exchanger 26 and introduced through line 27 into propane separator 28. Liquid propane is returned through line 29 to propane storage tank 11 and the carbon dioxide, 5 together with some vaporized propane is withdrawn through line 30 and introduced, with the carbon dioxide and propane leaving tower 14 through line 31 into the suction side of compressor 32. It should be noted that the pressure of the carbon dioxide and propane in line 31 is substantially the same as that in line 30, although it may be necessary to employ a pressure reduction valve in the latter line.

Compressor 32 raises the pressure of the carbon dioxide and propane to about 300 to 750 pounds per square inch, depending somewhat upon the temperature to which the compressed gases are cooled for liquefaction. The compressed gases are first cooled by condensing 20 water in cooler 33 and any propane which is liquefied may be separated from uncondensed carbon dioxide by closing valve 34 and by-passing the mixture through line 35 to propane trap 36, the separated propane being introduced through 25 line 37 and pressure-reducing valve 38 back into the top of the tower, and the carbon dioxide being withdrawn from the top of trap 36 through line 39 to line 40. Alternatively, valve 34 may be left open and the valves in lines 35 and 39 30 may be closed, so that both propane and carbon dioxide are passed through heat exchanger 21. In this heat exchanger the carbon dioxide is brought into counter-current thermal contact with cold filtrate so that the filtrate is appreciably warmed and the carbon dioxide is cooled and liquefied. The liquid carbon dioxide which may be at a temperature of about +30° F. to -30° F. is introduced through line 41 to trap 42, and the liquid carbon dioxide from the base of this trap supplies header 16 which has been hereinabove described. Any uncondensed gases which collect in the upper part of this trap may be vented through release valve 43 and line 44.

In my cooling and dewaxing system there is 45 no necessity for obtaining a sharp separation of propane from carbon dioxide. The propane which is carried with the carbon dioxide thru line 40 (i. e. is not separated in trap 36) is miscible with the liquid carbon dioxide and this 50 liquefied gas mixture is referred to as carbon dioxide even tho it may contain large amounts of propane. The propane itself serves a useful function when vaporized from injectors 17. To obtain the maximum benefits from my system, 55 however, a large proportion, at least, of the liquefied gas should be characterized by a vapor pressure which is substantially higher than that of the diluent employed.

Returning now to the propane recovery system, the depropanized oil from high pressure still 23 is withdrawn through line 45 and pressure-reducing valve 46 to low pressure oil still 47 which is provided with a suitable heater such as steam coil 48. Vapors from the top of still 65 47 are withdrawn through line 49, compressed by compressor 50 and introduced into line 25, cooler 26 and propane separator 28, as hereinabove described. Dewaxed oil is withdrawn from the base of low pressure still 47 through line 51 70 to storage or to any suitable finishing processes. It should be understood, of course, that this oil may be stripped with steam and blown bright with air or inert gas prior to its removal from the system, and that the vapors removed by the 75

stripping operations may be recovered and returned to the system.

The wax slurry which is removed from the filter through line 52 is introduced into high pressure wax still 53 which is provided with a suitable heater such as steam coil 54, and which is preferably operated at a pressure of about 200 pounds per square inch. Propane and dissolved carbon dioxide from the top of this tower may 10 be withdrawn through line 55 to line 25. Depropanized wax may be withdrawn through line 56 through pressure-reducing valve 57 and introduced into low pressure wax still 58 which is likewise provided with a suitable heater such as 15 steam coil 59. Propane from the low pressure still is withdrawn through line 60 to line 49 and the finally depropanized wax is withdrawn to storage or to sweating or finishing systems through line 61.

20 It should be particularly noted that the carbon dioxide and propane vapors which are removed from the top of tower 14 and which are returned through line 30 to line 31 are at a pressure of about 150 to 200 pounds per square 25 inch. This means that compressor 32 will have relatively light duty since it is only necessary to raise the pressure of these gases to about 300 to 750 pounds, preferably about 500 pounds.

A small amount of the carbon dioxide will 30 inevitably be carried with the propane into storage tank 11, and a small amount of the propane will inevitably be carried with the liquid carbon dioxide through trap 42 and header 16. The amount of gases or vapors thus dissolved do 35 not deleteriously effect the system and as hereinabove pointed out no sharp fractionation is necessary between the carbon dioxide and propane.

It should be understood that while I have 40 described carbon dioxide as a preferred example of my auxiliary refrigerant, the invention may also be practiced with other inert gases. It is important, however, that the gas have a sufficiently high vapor pressure under the desired 45 chilling conditions to effect refrigeration under the pressure maintained in tower 14, and when propane or other normally gaseous diluent is employed it is important that the vapor pressure of the auxiliary refrigerant be sufficiently higher 50 than the vapor pressure of the diluent to promote vaporization of the diluent into the auxiliary refrigerant gas in the cooling tower.

It should be understood that the above disclosure has been simplified to facilitate an understanding of the invention, and that in actual 55 practice additional desired heat exchangers, automatic controls and engineering expedients which are well-known to those skilled in the art will be employed in accordance with practice 60 well-known to those skilled in the art. I do not limit myself to the preferred embodiment or to the details hereinabove set forth except as defined by the following claims which should be construed as broadly as the prior art will permit.

65 I claim:

1. The method of dewaxing petroleum oil which comprises dissolving a wax-bearing petroleum oil in a diluent, introducing said diluent-oil solution at the top of a chilling zone and cascading the solution from the top to the bottom of 70 said zone, injecting a liquefied gas into said zone at spaced points along the length thereof to effect chilling and the liberation of gases and vapors, said gas having a vapor pressure substantially higher than the vapor pressure of the

diluent, regulating the amounts of injected liquefied gas introduced at each point to maintain a substantially uniform temperature gradient throughout the zone, withdrawing chilled slurry from the base of said zone, mechanically separating wax from said slurry and removing both gas and diluent from the separated wax and oil respectively. 5

2. The method of claim 1 wherein the liquefied gas is introduced into the chilling zone out 10 of direct contact with liquids in said zone.

3. The method of claim 1 which includes the steps of withdrawing gases and vapors from the top of said chilling zone, compressing said vapors, liquefying the compressed gases and vapors, separating liquid diluent from liquefied gases, returning liquefied diluent to the top of said chilling zone, and returning said liquefied gases at spaced points along said chilling zone. 15

4. The method of claim 1 wherein the diluent 20 is propane and the liquefied gas is carbon dioxide.

5. The method of continuously chilling a diluted wax-oil to effect the solidification of wax in separable form which comprises introducing said diluted waxy oil at the top of a chilling zone, 25 cascading said diluted oil from the top to the bottom of said chilling zone, introducing at spaced points along said chilling zone a liquefied gas of substantially higher vapor pressure than the vapor pressure of the diluent, whereby the 30 liquefied gas is vaporized throughout the length of the chilling zone, and whereby the vaporized liquefied gas promotes partial vaporization of diluent throughout the chilling zone, withdrawing chilled slurry from the base of said chilling 35 zone, separating wax from diluted oil, removing and compressing gases and vapors from the top of said chilling zone, cooling said compressed gases and vapors to obtain liquefaction thereof, and returning the liquefied gases at spaced points 40 along said cooling zone.

6. The method of claim 5 which includes the further step of separating liquefied diluent from the liquefied gas and returning the liquefied diluent at the upper part of said chilling zone. 45

7. The method of claim 5 which includes the further steps of distilling diluent and gas from wax and wax-free diluted oil, respectively, separating diluent containing dissolved gas from uncondensed gas and diluent vapors, diluting further quantities of oil with said diluent, and combining said uncondensed gas and diluent vapors with the gas and diluent vapors leaving the top of the chilling zone, and entering the compression step. 55

8. A continuous propane dewaxing process which comprises diluting a waxy oil with propane to form a waxy oil solution, introducing said solution at the top of a chilling zone, cascading said solution from the top of said chilling zone to the bottom thereof, introducing liquefied carbon dioxide at spaced points along said chilling zone, whereby the solution is chilled by vaporization of the carbon dioxide and by vaporization of propane into carbon dioxide gas throughout the length of the chilling zone, withdrawing a wax slurry from the base of the chilling zone, mechanically separating wax from the diluted oil, withdrawing carbon dioxide and propane from 70 the top of the chilling zone, compressing said carbon dioxide and propane to a pressure of about 300 to 750 pounds per square inch, cooling said compressed gases and vapors to effect liquefaction of the carbon dioxide, and returning the 75

liquefied carbon dioxide at said spaced points along said chilling zone.

9. The method of claim 8 which includes the further steps of distilling propane and carbon dioxide from said wax and diluted oil respectively, cooling said distilled carbon dioxide and propane to effect the liquefaction of most of the propane, returning the liquefied propane to the original waxy oil solution step and compressing 10 said gaseous carbon dioxide and propane along with the carbon dioxide and propane from the top of the chilling zone.

10. The method of operating a propane-carbon dioxide dewaxing system which comprises diluting a waxy oil with propane, continuously chilling 15 said propane-waxy oil mixture in a chilling zone maintained at a pressure of about 100 to 200 pounds per square inch by introducing liquefied

carbon dioxide at spaced points along said chilling zone whereby carbon dioxide and propane are vaporized in said zone, removing carbon dioxide and propane vapors from said zone, withdrawing chilled wax slurry from said chilling zone, separating said slurry into wax and diluted oil, recovering propane and carbon dioxide from said wax and diluted oil respectively at a pressure of about 100 to 200 pounds per square inch, compressing said recovered carbon dioxide and 10 propane together with the carbon dioxide and propane from the chilling zone, cooling the compressed carbon dioxide and propane to effect liquefaction thereof, and returning said liquefied carbon dioxide and said propane to said chilling 15 zone.
